[57] CLAIM

The ornamental design for a doll, as shown and described.

DESCRIPTION

FIG. 1 is a front elevation of a doll showing my design;

FIG. 2 is a right side elevation thereof;

FIG. 3 is a top plan view thereof;

FIG. 4 is a rear elevation thereof;

FIG. 5 is a left side elevation thereof; and

FIG. 6 is a front elevation thereof, similar to FIG. 1 without the tray.

The tray not shown in FIG. 6 is for the clarity of illustration.

FIG. 1

FIG. 2

FIG. 3

FIG. 4

FIG. 5

FIG. 6
